(57) **CLAIM**

The ornamental design for a bottle, as shown and described.

DESCRIPTION

FIG. 1 is a perspective view of the bottle of the present invention;

FIG. 2 is an elevational view of one side of the bottle, the other side being identical thereto;

FIG. 3 is a bottom plan view of the bottle; and,

FIG. 4 is a top plan view of the bottle.

The broken lines are for illustrative purposes only and form no part of the design.
